Alibaba.com, web search for artificial nails, date restricted to before Mar. 27, 2013.*

Primary Examiner — Jennifer Rivard

(57) **CLAIM**

The ornamental design for an artificial nail, as shown and described.

DESCRIPTION

FIG. 1 is a top front perspective view of the artificial nail showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines illustrate a portion of the artificial nail and form no part of the claimed design.
